(57) **CLAIM**

The ornamental design for a shoe as shown and described.

DESCRIPTION

FIG. 1 is a side view of a shoe showing my new design; FIG. 2 is a rear perspective view thereof; and, FIG. 3 is a front perspective view thereof.

The broken lines immediately adjacent to the rear and front of the shaded area define the bounds of the claimed design and form no part thereof. The unshaded interior surface of the patterned shapes and all other unshaded surface areas form no part of the claimed design. The broken lines depicting the remainder of the shoe form no part of the claimed design.
